UNITED STATES PATENT OFFICE.

CLAUDE A. LEWIS, OF HOUSTON, TEXAS, ASSIGNOR TO AMERICAN WINDOW COMPANY, OF HOUSTON, TEXAS, A CORPORATION OF DELAWARE.

RESILIENTLY-MOUNTED WINDOW SASH.

Application filed September 21, 1926. Serial No. 136,749.

My invention relates to windows such as are employed in offices, dwellings and other similar structures.

It is an object of the invention to mount 5 the window sashes so that they may be removed from the casing and in such manner as to allow the sliding of the lower sash within the frame.

It is another object to so mount the window 10 sashes that they will be held resiliently in position and offer a resistance to rattling or a play of the window sash relative to the rider or to the frame. It is desired to mount both sashes so that they may be approximately 15 reversed in position so as to expose the outer side of the window pane inwardly for cleaning.

The invention resides in the particular 20 mounting and the arrangement of the sash relative to the frame and these details will be pointed out with greater particularity in the specification which follows.

Referring to the drawing herewith, Fig. 1 is a transverse section through the frame 25 of a window involving my invention, the right-hand side being on a plane, including the lower sash, and the left-hand portion being on a plane through the upper sash. Fig. 2 is a front elevation of a window employing 30 my invention. Fig. 3 is a broken vertical section showing the provision for mounting the sashes therein. Fig. 4 is a vertical section through a window casing showing the two sashes in closed position therein. Figs. 35 5 to 8 inclusive are diagrammatic representations of the two window sashes shown in different operative positions to illustrate how they may be moved in the frame relative to each other. Fig. 9 is a broken front elevation 40 of the upper sash, certain parts being broken away for greater clearness. Fig. 10 is a side elevation of the upper sash. Fig. 11 is a broken front view of the lower sash, certain parts being broken away. Fig. 12 is a side 45 elevation of the lower sash, and Figs. 13 and 14 are side and front elevations respectively of the rider upon which the lower sash is mounted. Like numerals of reference are employed to designate like parts in all the 50 views.

In carrying out my invention, I contemplate that the window sash at the upper part of the frame will not be adapted to slide vertically in the frame but will be pivoted at 55 its lower end. The lower sash, however, is

adapted to slide vertically in the frame and also to be pivoted at its lower end to swing inwardly into the room. The window casing is of ordinary construction, having a window jamb 1 at the right-hand side of the casing 60 and a similar jamb 1' at the opposite side. The jamb comprises an upright plate at each side of the window with a stop member 2 at the outer side of the frame, this stop member furnishing a support for the outer side of 65 the upper sash 3. The lower sash 4 is mounted upon riders 5 at each end. The jambs 1 and 1' are formed with channels 6 therein to receive the riders. Sash cords 7 are secured to the riders, said cords being secured 70 to sash weights 8 in the usual manner.

The lower sash is formed for attachment to the rider 5 at both its upper and lower ends. As shown in Fig. 11, the upper end of the sash has a laterally projecting pin 9 to be 75 received within a slot 10 in the upper end of the rider. The lower end of the lower sash has a recess 11 therein, said recess being tapered from the lower end upwardly to a point approximately midway between the 80 ends of the sash. This recess, as shown in Fig. 12, is of sufficient width to allow play therein of a spring 12. Said spring is a flat plate of resilient metal secured by screws 13 to the sash at the upper end of the recess 11. 85 The lower end extends to a point approximately flush with the lower end of the sash and has an outwardly projecting pin 13 thereon to fit within a corresponding recess 14 in the rider. The spring plate 12 is adapted to 90 be pressed resiliently outward so as to hold the pin 13 thereon resiliently within the opening 14 in the rider.

The rider for the lower sash is shown in Figs. 13 and 14. It comprises an upper 95 member 15 and lower member 16. Said members being connected resiliently together. The upper end is grooved on its outer face adjacent the casing to receive the sash cord 7 and an opening extends from the lower end of said groove through the body of the member 15 to better secure the cord in place. Screws 17 are employed to further secure the cord against removal from the groove. On the inner side of the upper member 15 is 100 formed the groove 10 closed at its lower end and open at the upper end to allow the pin 9 on the sash to be freed from the rider.

The lower end 16 of the rider is beveled at 105 18 to fit the window frame and the upper end 110

has attached thereto a strap of metal 19 formed in the shape of an inverted U, the legs thereof being set within the sides of the member 16 and held in position by screws 20. 5 The upper end of the plate 19 extends about the portion 16 and has a central opening to receive a screw 21 secured within the lower end of the upper member 15. The lower end of the screw 21 is cylindrical and is 10 slideable within the plate 19 for a limited distance. A spring 22 is placed about the lower shank of the screw and serves to hold the two members 15 and 16 resiliently apart. It will be obvious therefore that the sash may be 15 mounted upon the rider by connecting the lower pins 13 upon the sash within the openings 14 in the rider. The sash may be then pulled upwardly to bring the pin 9 within the upper end of the groove 10 and in doing so 20 the spring 22 will be compressed to allow the shortening of the rider. When the pin 9 is within the groove the tension upon the spring 22 will tend to force the pins 9 and 10 apart, thus holding the pins firmly within the 25 openings in the rider and preventing play thereof.

The upper sash 3, shown in Figs. 9 and 10, has at its lower end on each side thereof recesses 11' and springs 12' similar in all respects to the springs upon the lower sash. 30 Pins 13' on said springs are adapted to fit within openings 23 in the window jamb 1' and 1 as shown in Fig. 3.

In operating my window, it will be possible to reverse the lower sash by raising it 35 along with its rider to the upper end of the casing. I provide a narrow stop member 24 at the upper forward side of the channel 6 in the casing, and against this stop the rider will engage and be thus limited in its upward movement. If the sash is then pushed 40 further upward the spring 22 upon the rider will be compressed and the pin 9 upon the sash will be lifted out of the groove 10. I provide a groove 25 in the forward side of 45 the window jamb in front of the channel 6, through which the pin 9 may be moved when the lower sash has been raised to free the pin from the groove 10. Thus the sash may be 50 swung inwardly at its upper end from the position shown in Fig. 5 to that shown in Fig. 6, thus bringing the outer face of the window pane inwardly for cleaning or otherwise. In this swinging movement the lower pins 13 are held firmly within the recesses 14 55 in the riders to form a pivot.

While the lower sash is in its reversed position, the upper sash may be then moved inwardly about the pivot formed by the pins 13' into the position shown in Fig. 7. It will 60 be noted that the upper sash is somewhat limited in its swinging movement by the upper end of the lower sash so that the upper sash may not be entirely reversed. The upper face, however, will be exposed in the 65 room for cleaning.

It sometimes is desirable to have the window closed except for a vent at the upper end and provision is made to allow the upper end of the upper sash to swing inwardly to a certain extent, as shown in Fig. 8. This 70 swinging movement is accommodated by the forming of the contact faces of the two sashes shown in Fig. 4. The lower end of the upper sash is beveled forwardly to provide a face 26 to contact against the face 27 of the 75 lower sash. The upper portions of the adjacent sash faces are beveled to provide a space indicated at 28 to allow a limited movement inwardly of the upper sash as indicated. This will allow a vent at the upper end without necessitating the unlocking of the sash except at the upper end, and it is understood that means may be provided, if desired, to lock the upper end of the sash in adjusted position. 80

The advantages of this type of window lie in the resilient and positive connection between the two sashes and their supports. The upper sash is connected at its lower end firmly with the casing. The lower sash is similarly pivoted and it is held tightly in contact with the rider through the resilient action of the spring 22, tending to hold the pins 9 and 13 away from each other and into frictional contact with the recesses in which they fit. In removing the sashes from their supports, it will be necessary to compress the springs 12 and 12'. These springs will be accessible for compression only when the sashes have been swung inwardly, as previously described, to such an extent as to expose the springs after which the pins 13 or 13', as the case may be, may be forced inwardly toward the sashes and into the recesses 11 to allow the removal of the pin 13 105 and 13' in an obvious manner.

The further advantages of this construction will be apparent to those skilled in the art.

Having thus described my invention, what 110 I claim as new and desire to protect by Letters Patent is:

1. In a window, a casing having opposite channels therein, and forwardly curved 115 grooves communicating therewith adjacent the upper ends thereof, riders slideable in said channels, said riders having upwardly opening grooves at their upper ends and pin-receiving recesses at their lower ends, a sash on said riders, upper and lower pins fitting within said grooves and said recesses respectively, and means to hold said lower pins resiliently within said recesses. 120

2. In a window, a casing having opposite channels therein, and forwardly curved 125 grooves communicating therewith adjacent the upper ends thereof, riders slideable in said channels, said riders having upwardly opening grooves at their upper ends and pin-receiving recesses at their lower ends, a sash on 130

- said riders, upper and lower pins fitting within said grooves and said recesses respectively, and means to hold said lower pins resiliently within said recesses, and means adjacent said 5 forwardly curved grooves to limit the upward movement of said riders, said grooves allowing said upper pins to be moved inwardly.
3. In a window, a casing having opposite 10 channels therein, and forwardly curved grooves communicating therewith adjacent the upper ends thereof, riders slidable in said channels, said riders having upwardly opening grooves at their upper ends and pins receiving recesses at their lower ends, a sash on said riders, upper and lower pins fitting within said grooves and said recesses respectively, and means to hold said lower pins resiliently within said recesses, said riders 15 being longitudinally extensible to allow said upper pins to be moved upwardly into registration with said forwardly curved grooves.
4. In a window, a casing, riders slidable in channels in said casing, a sash on said riders, 20 laterally-extending pins on said sash, fitting within said riders, there being upwardly opening recesses for the upper pins, and means to allow said upper pins to be moved upwardly free of said rider, while said lower 25 pins remain without upward movement relative to said rider to form a pivot for said sash.
5. In a window, a casing, riders slidable in channels in said casing, a sash on said riders, laterally-extending pins on said sash, fitting 30 within said riders, there being upwardly opening recesses for the upper pins, and means to allow said upper pins to be moved upwardly free of said rider, while said lower pins remain in position in said rider to form 35 a pivot for said sash, and means to hold said lower pins resiliently in position in said sash.
6. In a window, a casing, riders slidable in channels in said casing, a sash on said riders, laterally-extending pins on said sash, fitting 40 within said riders, there being upwardly opening recesses for the upper pins, and means to allow said upper pins to be moved upwardly free of said rider, while said lower pins remain in position without vertical or 45 lateral support relative to said rider to form a pivot for said sash, said lower pins being releasable from said riders only when said sash is swung inwardly at its upper end.
7. In a window, a casing, riders slidable 50 vertically in channels therein, said riders having upwardly-opening grooves at their upper ends and cylindrical recesses at their lower ends, a window sash, pins thereon engaging in said grooves and recesses, and means to 55 vary the distance between the said recesses and said grooves to release said upper pins, said casing being grooved to allow the upper pins and said sash to swing forwardly.
8. In a window, a casing, riders slidable 60 vertically in channels therein, said riders having upwardly-opening grooves at their upper ends and cylindrical recesses at their lower ends, a window sash, pins thereon engaging in said grooves and recesses, said riders being compressible longitudinally to allow said upper pins to be released from said riders for the purpose described.
9. In a window, a casing, riders slidable 65 therein, a sash on said riders, pins at the upper and lower ends of said sash engaging in recesses in said riders, means to hold said lower pins resiliently in position in said recesses, and means to hold said pins frictionally in said upper recesses.
10. In a window, a casing, riders slidable 70 therein, a sash on said riders, pins at the upper and lower ends of said sash engaging in recesses in said riders, means to hold said lower pins resiliently in position in said recesses, and means to hold said pins frictionally in said upper recesses comprising spring means in said riders tending to force the ends of said riders apart.
11. In a window, a casing, riders slidable 75 therein, a sash on said riders, pins at the upper and lower ends of said sash engaging in recesses in said riders, said lower pins being mounted on spring plates, said upper pins being releasable from said riders.
12. In a window, a casing, sash supporting 80 means in said casing having cylindrical recesses therein, sash in said casing, laterally extending pins on said sash adapted to fit in said recesses to be pivoted thereon, and means to hold said pins resiliently in position.
13. In a window, a casing, window jambs 85 therein having cylindrical recesses therein, upper sash in said casing, laterally projecting pins in said sash shaped and positioned to engage said recesses, said pins being mounted on springs tending to retain them resiliently 90 in said recesses.
14. In a window a casing, window jambs 95 therein, riders slidable vertically in channels in said jambs, said riders being extensible in length, a sash, and upper and lower pins thereon engaging recesses in said riders, the uppermost pins being releasable.
- In testimony whereof I hereunto affix my signature this 11th day of September, A. D. 1926.

CLAUDE A. LEWIS.
